UNITED STATES PATENT OFFICE.

JAMES M. LAFLIN, OF BOISE, IDAHO.

COMBINATION PLIERS AND WRENCH.

Application filed August 14, 1923. Serial No. 657,286.

To all whom it may concern:

Be it known that I, JAMES M. LAFLIN, residing at Boise, in the county of Ada and State of Idaho, whose post-office address is 413 Broad Street, Boise, Idaho, a native-born citizen of the United States, have invented certain new and useful Improvements in Combination Pliers and Wrenches, of which the following is a specification.

My present invention relates to combination pliers and wrenches, and particularly to a tool of the cross handle type.

An object of this invention is to provide a tool which can be used as pliers or a wrench, without adjustment or manipulation of the parts for the interchangeable use.

A further object is to provide a tool of this character which is so constructed that the jaws can be of tool steel or other suitable hardened and wear-resisting metal, while the handles and remaining portions can be of any other suitable metal which can be readily worked and shaped.

A still further object resides in so constructing and assembling the parts that the jaw portions can be readily removed and replaced, without the use of special tools or equipment.

Another object is to provide a tool of this character in which the main working bearing is contained within the jaw structure.

With these and other objects in view, which will be apparent from the description and drawings, my invention includes certain novel features of construction and combination of parts which will now be set forth and then pointed out in the claims.

In the drawings:

Figure 1 is a plan view of a tool constructed in accordance with this invention.

Fig. 2 is a view in edge elevation.

Fig. 3 is a view similar to Fig. 1 taken from the opposite side.

Fig. 4 is a plan view of one of the handle members.

Fig. 5 is an edge elevation of the member shown in Fig. 4.

Fig. 6 is a view similar to Fig. 4 showing the remaining handle member.

Fig. 7 is an edge elevation of the member shown in Fig. 6.

Fig. 8 is a transverse sectional view on line 8—8 of Fig. 1.

Fig. 9 is a sectional view on line 9—9 of Fig. 1.

Fig. 10 is a plan view of the jaws.

The handles 1 and 2 are curved, as at 3 and 4, so that the handle portions lie in substantially parallel relation and the ends 5 and 6, corresponding to the jaw portions of the usual pliers, are crossed, and are in opposed relation. The ends 5 and 6 are recessed as at 7 and 8, and are provided with the bearing ears 9 and 10, which ears are off-set to interfit when the handles are placed in crossed relation. The ends 5 and 6 are provided with openings 11 and 12, extending substantially parallel with the openings of the bearing ears 9 and 10, and these ends are recessed as at 13 and 14 on adjacent sides.

The jaw members 15 and 16 are substantially semi-circular in outline to fit within the recesses 7 and 8 of the ends 5 and 6 of the handles, and these jaw members are provided with interfitting bearing ears 17 and 18. A pin 19 is riveted or otherwise secured in the openings of the bearing ears to pivotally connect the jaw members 15 and 16, and this pin has an extending screw-threaded end 20 adapted to fit through the openings of the ears 9 and 10 of the handle members when the jaw members are fitted in the recesses 7 and 8, a nut 21 being turned onto the threaded end 20 to hold the parts in assembled position. Pins 22 and 23 are connected in the ends of the jaw members 15 and 16 and are provided with threaded extending ends 24, which fit through the openings 11 and 12 of the handle members, nuts 25 and 26 being turned onto these threaded ends to rigidly hold and secure the jaw members within the recesses 7 and 8 of the ends 5 and 6 of handle members 1 and 2.

The adjacent faces of jaw members 15 and 16 are recessed as at 27 and 28 to give an opening of polygonal form when the plier handles are opened, and the abutting faces 29 and 30 of these jaw members might be scored or otherwise roughened to give a better grip when the tool is used as a gripping plier. Also, the faces 31 and 32 of the ends 5 and 6 may be scored or roughened. The recesses 13 and 14 of these ends

5 and 6 can be increased in size and pairs of jaw members having wrench socket recesses or openings of different sizes and configurations can be fitted and used in conjunction with the pliers handles.

While I have herein shown and described only certain specified embodiments and have set forth only certain possible modifications, it will be appreciated that various changes 10 and modifications can be made in the form, arrangement and manner of assembling the parts, without departing from the spirit and scope of my invention.

I claim:

15 1. A combination plier and wrench, comprising a pair of crossed handles having bearing ears spaced from the point of crossing and having their ends recessed adjacent said ears, a pair of jaws pivotally connected 20 together adapted to be fitted within the recesses with their pivot mounting in line with the bearing ears, and means to hold the jaws in place in the recesses.

2. A combination plier and wrench, comprising a pair of handle members curved to cross adjacent their ends and having said ends recessed on adjacent faces, a pair of

jaws adapted to fit within the recesses pivotally connected together, and means to secure said jaws within the recesses and pivot 30 said handles for swinging movement.

3. A combination plier and wrench comprising a pair of handle members, each curved adjacent one end to be fitted in crossed relation and having the crossed ends 35 recessed on adjacent faces, said recessed ends being provided with bearing ears and having openings at points spaced from said ears, a pair of jaw members provided with interfitting bearing portions, a pin pivotally connecting said jaw members having a threaded extension to fit through the bearing ears of the handle members when the jaws are fitted in the recesses, a nut turned onto the threaded end to hold the handles 40 in assembled relation, threaded pins carried by said jaw members to fit through the openings of the recessed ends and nuts turned onto said threaded pins to secure the jaw members in place.

In testimony whereof I hereunto affix my signature.

JAMES M. LAFLIN.
